[57] CLAIM

The ornamental design for an amusement toy, as shown and described.

DESCRIPTION

FIG. 1 is a front elevational view of an amusement toy showing my new design;

FIG. 2 is a rear elevational view thereof;

FIG. 3 is a top plan view thereof;

FIG. 4 is a bottom plan view thereof; and,

FIG. 5 is a right side elevational view thereof, the left side view being a mirror image thereof.

The characteristic feature of the claimed design resides in the specific configuration and ornamentation of the interior members as shown and described in FIGS. 1, 2, and 5.

FIG. 1.

FIG. 2.

FIG. 3.

FIG. 5.

FIG. 4.
